[57] CLAIM

The ornamental design for a crimping tool, as shown and described.

DESCRIPTION

FIG. 1 is a top plan view of the crimping tool showing our new design;

FIG. 2 is a side elevational view thereof, the opposite side being identical;

FIG. 3 is a front end elevational view thereof;

FIG. 4 is a rear end elevational view thereof;

FIG. 5 is a sectional view thereof taken along line 5—5 of FIG. 1 the handle being shown broken away for illustrative purposes only; and

FIG. 6 is a perspective view thereof.
